CLAIM

The ornamental design for a toilet brush kit, as shown and described.

DESCRIPTION

FIG. 1 is a perspective view of a toilet brush kit showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view, showing the toilet brush kit in a state of use.

The shading is utilized to illustrate the surface contours of the toilet brush kit design in the drawings.

The broken lines in the drawings depict portions of the toilet brush kit that form no part of the claimed design.
